[57] CLAIM

The ornamental design for a photo storage case, substantially as shown and described.

DESCRIPTION

FIG. 1 is a perspective view of a photo storage case showing our new design;

FIG. 2 is an exploded perspective view thereof;

FIG. 3 is a perspective view of the lower tray section, the other tray sections and cover being omitted for convenience of illustration; and

FIG. 4 is a bottom perspective view thereof.

FIG. 2

FIG. 1

FIG. 4
